US00D758369S

(12) **United States Design Patent**
Kuroda et al.

(10) **Patent No.:** **US D758,369 S**
(45) **Date of Patent:** **** Jun. 7, 2016**

(54) **SCANNER**

(71) **Applicant:** **PFU LIMITED**, Kahoku-shi, Ishikawa (JP)

(72) **Inventors:** **Satoshi Kuroda**, Kahoku (JP); **Shoya Ishida**, Kahoku (JP); **Motoshi Shibuya**, Kahoku (JP); **Ryuichi Nagai**, Kahoku (JP)

(73) **Assignee:** **PFU LIMITED**, Ishikawa (JP)

(**) **Term:** **14 Years**

(21) **Appl. No.:** **29/520,959**

(22) **Filed:** **Mar. 19, 2015**

(30) **Foreign Application Priority Data**

Sep. 30, 2014 (JP) 2014-021617

(51) **LOC (10) Cl.** **14-02**

CLAIM

The ornamental design for a scanner, as shown and described.

DESCRIPTION

FIG. 1 is a front perspective view of a scanner showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof; and,

FIG. 8 is another front perspective view thereof showing the guides for both paper feed and catch trays in an extended condition.

Broken lines and unshaded portions contained within broken lines are not claimed.

1 Claim, 5 Drawing Sheets
